US0D1070024S

(12) **United States Design Patent** (10) Patent No.: **US D1,070,024 S**
(45) Date of Patent: ** Apr. 8, 2025

(54) **DRAIN GRATE**

(71) Applicant: **Zurn Water, LLC**, Milwaukee, WI
(US)

(72) Inventors: **Karam Ghazalah**, Milwaukee, WI
(US); **Christopher J. Say**, Milwaukee,
WI (US)

(73) Assignee: **Zurn Water, LLC**, Milwaukee, WI
(US)

(**) Term: **15 Years**

(21) Appl. No.: **29/812,667**

(22) Filed: **Oct. 22, 2021**

Related U.S. Application Data

(63) Continuation of application No. 17/239,466, filed on
Apr. 23, 2021, now Pat. No. 11,795,703.

(51) **LOC (15) Cl.** **23-01**

(52) **U.S. Cl.**

(57) **CLAIM**

The ornamental design for a drain grate as shown.

DESCRIPTION

FIG. 1 is a top perspective view of a drain grate.

FIG. 2 is a bottom perspective view of the drain grate of FIG. 1.

FIG. 3 is a top view of the drain grate of FIG. 1.

FIG. 4 is a bottom view of the drain grate of FIG. 1.

FIG. 5 is a left-side view of the drain grate of FIG. 1.

FIG. 6 is a right-side view of the drain grate of FIG. 1.

FIG. 7 is a back view of the drain grate of FIG. 1; and,

FIG. 8 is a front view of the drain grate of FIG. 1.

The evenly spaced broken lines in the drawings show portions of the drain grate, which form no part of the claimed design. The dash-dot broken lines define the bounds of the claimed design and form no part thereof.

1 Claim, 6 Drawing Sheets

US D1,070,024 S
